UNITED STATES PATENT OFFICE.

ELBRIDGE D. FARNHAM, OF MILTON MILLS, NEW HAMPSHIRE.

BEVEL.

SPECIFICATION forming part of Letters Patent No. 339,633, dated April 13, 1886.

Application filed December 29, 1885. Serial No. 187,042. (No model.)

To all whom it may concern:

Be it known that I, ELBRIDGE D. FARNHAM, a citizen of the United States, residing at Milton Mills, in the county of Strafford and State of New Hampshire, have invented certain new and useful Improvements in Squares; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to try-squares of that class in which the blade portion is made adjustable relative to the handle or stock; and it consists in the novel features shown and more fully hereinafter set forth and specifically claimed.

20 In the drawings, Figure 1 is an elevation of my improved square, the dotted lines showing some of its various adjustments. Fig. 2 is a view looking in the direction of the arrow, Fig. 1. Fig. 3 is a view of the blade detached. Fig. 4 is a detail section through the end of the stock and blade, showing the clamp-screw for holding the blade in an adjusted position.

25 The handle or stock is made in two corresponding parts, A A', each of which consists of a metal frame, B, veneered by a wooden piece, C. The ends of the faces designed to lie adjacent to each other are slightly projected to form a space, D, when the parts are together. The rear ends are secured by rivets a. The blade E is held between the front ends of the stock by a set-screw, F, passed loosely through one part of the blade and screwed 40 into the other part. The forward ends are rounded or semicircular and reduced in thickness for an equal distance from the rounded edge, as indicated at b, leaving a raised portion around the opening through which the 45 set-screw passes. This reduced portion is beveled outward, and has a series of notches, d, formed therein. The notches in each end correspond and coincide with each other.

The blade E has an opening, e, near its outer edge, so disposed that a line drawn at right angles from either parallel edge will pass through the center of said opening e and the center of the pivot-opening f. Opening e is preferably oblong, and its lower half, or that

part nearest the pivot-opening, corresponds 55 with the notches d in the ends of the stock.

The notches are graduated and indicate any desired angle; or the square may be used as a straight-edge, which positions are clearly indicated in dotted lines, Fig. 1.

60 By having the notches d in each end of the parts of the stock correspond and coincide, and the opening e in the blade likewise partially correspond with the notches, greater precision and nicety of adjustment may be had. 65 For instance, if it is desired to set the blade at a certain angle to the stock, the set-screw is slackened, when the blade may be turned till the opening e comes opposite the notch indicating the desired angle, and, in order that 70 a true alignment of the notches and opening may be had, irrespective of sighting, a tapering key may be inserted through such opening e, when it will be made to coincide with the notches. Then by tightening the set-screw 75 the device is ready for use, the parts being prevented from slipping by the key, which may be left in place till the blade is securely clamped.

Having thus described my invention, what I 80 claim, and desire to secure by Letters Patent, is—

1. The combination, with the stock having semicircular ends notched around their edge, of a blade pivotally secured between said ends 85 and provided with an opening to register with the notches, whereby a true alignment may be obtained by the insertion of a tapering instrument through the opening and notches, substantially as hereinbefore specified. 90

2. A try-square composed of the following elements, in combination: a stock made in two parts secured together, leaving a space between them, each part terminating in semicircular reduced ends having corresponding 95 radial notches, a blade adjustably clamped between the ends by a set-screw, and having an oblong opening at one side of the pivot-opening on a line drawn at right angles from one side through the pivot-opening, one-half 100 of said opening corresponding with the notches in the semicircular ends, substantially as and for the purposes set forth.

In testimony whereof I affix my signature in presence of two witnesses.

Witnesses: ELBRIDGE D. FARNHAM.

JOSHUA M. YOUNG,

ALFRED R. WORMWOOD.
